Edouard Urban & Clair Seel

By Edward C. Sargent,
Attorney.

UNITED STATES PATENT OFFICE.

EDOUARD URBAIN AND CLAIR SCAL, OF PARIS, FRANCE.

MAGNETO.

Application filed July 25, 1921. Serial No. 487,478.

(GRANTED UNDER THE PROVISIONS OF THE ACT OF MARCH 3, 1921, 41 STAT. L., 1313.)

To all whom it may concern:

Be it known that we, EDOUARD URBAIN and CLAIR SCAL, citizens of the Republic of France, and residing at 30 Avenue de l'Observatoire, Paris, France, and 49 Rue Vaneau, Paris, France, have invented certain new and useful Improvements in or Relating to Magneto's, for which we have been granted a patent in France No. 517,413, Dec. 17, 1920, 10 of which the following is a specification, reference being had therein to the accompanying drawing.

Ignition devices for explosion engines comprise a so-called low tension magneto discharging into condensers, which condensers afterwards discharge into the primary of an induction apparatus, and in the secondary of which is obtained the high tension necessary for the sparking plugs. 20 In an apparatus of small power and volume, the advantages of the great simplicity of this system are offset by a serious drawback, in that there is delay in the charging of the condensers, and this delay increases with the speed.

The delay is all the more pronounced since, instead of using a strictly sinusoidal form of wave, it is sought to approximate it to the shape of a rectangle, in order to obtain quicker flux variations, and consequently higher potentials for the low speeds. The harmonics are not shifted in the same way at the different speeds, and the intensity curves corresponding to the different speeds, 30 are very dissimilar.

This invention has for its objects to eliminate the injurious effects of the said delays, and to give a fixed advance to the ignition, beginning with a certain speed, and these objects are accomplished by:—

1.—Short-circuiting the armature during a fraction of the period, immediately prior to charging the condenser.

2.—Breaking the said short-circuit, which produces the charging of the condensers at low speeds.

3.—Breaking the condenser-armature circuit, after which the condenser remains charged.

50 4.—Discharging the condenser at the end of a certain time into the primary of the induction apparatus.

5.—Suppressing the breaking of the armature-condenser circuit on a certain speed

being reached, which makes it possible to 55 give an advance to the ignition if the discharge of the condenser into the primary of the induction apparatus of the stage 4 has been sufficiently retarded.

One embodiment of the invention is shown 60 diagrammatically in the accompanying drawings, in which:

Fig. 1 is a diagram showing the connections of the disc and of the shoes with parts of a magneto. 65

Figs. 2, 3 and 4 are detail views showing different positions of the disc relatively to the shoes.

Figs. 5 and 6 are views similar to Fig. 1, showing different positions of the switch 70 which is intended in one position to give a fixed advance to the ignition at high speeds and in another position to cut out the ignition.

The disc 1, that is made of a good conductive material, comprises four sectors, of which two (3, 3) are of good conductivity, being constituted, for instance, by two symmetrical parts of the disc, and the two others (2, 2) are insulating parts, being constituted, for instance, by recesses of the disc. Said disc is rigidly mounted on the shaft of the magneto, from which latter it is electrically insulated; it turns at the same speed as the said shaft of the magneto. 80

The armature of the magneto may be mounted on the axle, as in the largest number of magneto's, or it may be stationary as in the magneto's with rotatable magnets. One of the poles of the armature is earthed 90 and the other pole is connected directly, or through a brush, to the disc 1.

In the drawings the magneto is shown very diagrammatically. 7 is the armature, of which the pole 8 is connected to the disc 1, 95 and the other pole 9 is earthed.

Two shoes 4 and 5 are placed so as to press on the full parts 3, 3 of the disc 1, and so as not to fall in the recesses 2, 2 of said disc, this result being obtained by limiting the displacement of said shoes or by filling up the recesses 2, 2 with some insulating material. 100

The shoe 4 is earthed or connected to the mass of the magneto, as at 10, while the shoe 5, that is insulated from the mass, is connected to the pole 11 of the condenser, the other pole 12 being earthed, or connected 105

to the mass 10, through the primary 13 of the transformer.

The different positions of disc 1 that correspond to the different phases of the working of the magneto are as follows:

1. When the disc 1 is in one of the positions shown in Figs. 1 and 4, the shoe 4 presses against one of the sectors 3 and the armature of the magneto is short-circuited, the pole 8 being earthed through 1 and 4.

2. When the disc 1 is in the position shown in Fig. 2, the shoe 4 has just abandoned one of the sectors 3 and is in front of one of the parts 2, the other shoe 5 being

15 in contact with the other sector 3; a breaking takes place and the induction current at breaking charges up the condenser through the shoe 5.

3. When the disc is in the position shown in Fig. 3, the shoe 5, in its turn, abandons the corresponding sector 3 and the condenser, being insulated, remains charged.

4. When the disc is in the position shown in Fig. 4, the two shoes 4 and 5 are in contact with the conductive parts of disc 1. The shoe 4 has been first attained by one of the sectors 3 and the armature of the magneto has been again short-circuited.

Then the shoe 5 comes in contact with 30 the other sector 3, and the pole 11 of the condenser is then earthed or connected to the mass through 5, 1 and 4.

The discharging of the condenser takes place suddenly, through the intermediary of 35 the primary 13 of the transformer on the one hand, and through 5, 1 and 4 on the other hand. This sudden discharge produces in the secondary 14 of the transformer the current giving the ignition spark.

40 By the choice of the relative dimensions of the sectors 3 and of the relative dimensions and positions of the shoes 4 and 5, it is possible to retard broadly this latter contact and to produce the spark with a retardation greater than the retardation due even at high speeds to the phenomenon of self induction in the armature.

5. At high speeds, the shoe 5 is placed out of circuit (Fig. 5) by directly connecting the pole 11 of the condenser to the pole 8 of the armature; a fixed advance to ignition is thus obtained if an arrangement has been made so that the mechanical retardation at small speeds should be greater than the functional electric retardation which alone comes into action at high speeds.

This result is obtained through the use of the switch 6 that is placed in the position shown in Fig. 5, wherein 11 is connected to 8 through disc 1.

Fig. 6 shows switch 6 in a position short-circuiting the armature and thus cutting out the ignition.

65 One of the chief advantages of this device consists in the fact that if accidentally after

a stoppage, the advance of the ignition persists, the starting of the engine will become practically impossible, for the speed to be given to the engine for obtaining a spark, exceeds anything that can be obtained by means of the starting handle. Any risk of back firing when starting, is therefore eliminated.

It is obvious that any other mechanical device may be used for obtaining the five successive stages described; for instance, fixed contact-breakers could be controlled by movable bosses acting in the desired sequence.

The switching out of the brushes insulated from the mass by the continuous electric connection of the condensers to the disc, may also be effected outside the magneto, at any desired distance and if desired this may be rendered automatic.

It must be clearly understood that the mechanical and electric construction hereinbefore described in detail is not intended in any way to restrict the generality of the principles hereinbefore set forth, or to limit the scope of the invention.

What we claim is:

1. In an ignition system for internal combustion engines, a primary circuit including a generator, a condenser and primary coil, and switch mechanism operating in synchronism with said generator and, successively, short-circuiting the armature of said generator, closing the primary circuit through said armature, breaking said short-circuit, opening the primary circuit, and finally closing the primary circuit exclusive of said armature.

2. In an ignition system for internal combustion engines, a primary circuit including a condenser and primary coil, a magneto, switch mechanism operating with the armature of said magneto and periodically performing the following functions in succession: short circuiting said armature, closing the primary circuit through said armature, opening said short circuit, opening the primary circuit, closing the primary circuit exclusive of said armature.

3. In an ignition system for internal combustion engines, a partial circuit including a condenser and a primary coil, a generator, a first terminal connected to one side of said partial circuit, a second terminal connected to the other side of said partial circuit and to one pole of said generator, and switch mechanism operating in synchronism with said generator and periodically performing the following functions in succession: connecting said second terminal with the other pole of said armature, connecting said first terminal with said other pole, disconnecting said second terminal, disconnecting said first terminal, connecting said terminals.

4. In an ignition system for internal com-

- bustion engines, a partial circuit including a condenser and primary coil, a generator, a first terminal connected to one side of said partial circuit, a second terminal connected 5 to the other side of said partial circuit and to one pole of said generator, switch mechanism rotating with said armature and performing the following functions in succession: connecting said second terminal with 10 the other pole of said armature, connecting said first terminal with said other pole, disconnecting said second terminal, disconnecting said first terminal, connecting said terminals; and a manually operated switch 15 adapted to cut out said first terminal and connect said other pole of the armature to the first-mentioned side of said partial circuit.
5. In an ignition system for internal combustion engines, a partial circuit including a condenser and primary coil, a generator, a conductive disc rotating in synchronism with said generator and electrically connected to one pole of the armature thereof, a 20 first brush contacting said disk and electrically connected to one side of said partial circuit, a second brush contacting said disc on the opposite side of the axis of rotation thereof from said first brush and connected 25 to the other side of said partial circuit and to the other pole of said armature, opposite portions of said disc adapted to break electrical contact with said brushes and said brushes being so arranged that said second brush makes 30 electrical contact with said disc in advance of said first brush, and a switch adapted to one position to close a connection between said disc and said first brush and in another position to close a connection between said disc and said second brush.
6. In an ignition system for internal combustion engines, a partial circuit including a condenser and primary coil, a magneto, a 35 conductive disc rotating with the armature of said magneto and electrically connected to one pole of said armature, a first brush contacting said disc and electrically connected 40 to one side of said partial circuit, a second brush contacting said disc on the opposite side of the axis of rotation thereof from said first brush and connected 45 to the other side of said partial circuit and to the other pole of said armature, opposite portions of said disc adapted to break electrical contact with said brushes and said brushes being so arranged that said second brush makes electrical contact with said disc in advance of said first brush, and a switch adapted to close a connection between said disc and said first brush and to close a connection between said disc and said second brush.
7. In an ignition system for internal combustion engines, a partial circuit including a condenser and primary coil, a magneto, a conductive disc rotating with the armature of said magneto and electrically connected to one pole of said armature, a first brush contacting said disc and electrically connected to one side of said partial circuit, a second brush contacting said disc on the opposite side of the axis of rotation thereof from said first brush and connected to the other side of said partial circuit and to the other pole of said armature, opposite portions of said disc adapted to break electrical contact with said brushes and said brushes being so arranged that said second brush makes electrical contact with said disc in advance of said first brush, and a switch adapted to close a connection between said disc and said first brush and to close a connection between said disc and said second brush.
8. In an ignition system for internal combustion engines, a primary circuit including a condenser and primary coil, a magneto, and switch mechanism rotating with the armature of said magneto and, successively, short-circuiting the said armature, closing the primary circuit through said armature, breaking said short circuit, opening the primary circuit, and finally closing the primary circuit exclusive of said armature.

In testimony whereof we hereunto affix our signatures.

EDOUARD URBAIN.
CLAIR SCAL.
